GEORGE R. KRESS, OF LOS ANGELES, CALIFORNIA.

MEANS AND METHOD FOR MOVING LARGE BUILDINGS.

Application filed March 19, 1929. Serial No. 348,194.

This invention relates to the art of moving buildings, and is directed particularly to a novel method for moving large building structures which are several stories in height and in which the weight of the building is supported by a plurality of load members, such as columns. Such buildings will, for the purpose of defining this invention, be hereinafter referred to as column supporting building structures.

It is frequently necessary during street improvements in large cities where the street is being widened, to move the building front several feet back from its original position. This can be readily accomplished in small buildings where the weight of the building is supported by a side foundation, by elevating the building a sufficient distance to get movable supports, in the form of rolling members, between the side walls of the building and the foundation, and after supporting the building in this manner moving the same bodily to the desired position.

Business buildings are, however, generally constructed to cover completely the lot upon which they are built, and under such conditions it is necessary either to completely tear down the front of the building, reconstructing the same at the desired position, or to move the front of the building rearwardly in a manner such as is disclosed in my copending application, Serial No. 339,025, filed February 11, 1929.

The method last referred to is not adapted for use in buildings over three or four stories in height, where the major portion of the building is supported by columns and in which the movement of a single wall of considerable height would be a hazardous undertaking. The operation of "setting in" large building fronts of this character has heretofore been carried out by tearing down the building front and constructing a new front in the desired position. Such an operation is obviously very costly, due to the time consumed and also in view of the fact that the fronts of such buildings are generally made of finer material than the side walls.

Large buildings of this character are ordinarily provided with light wells at an intermediate point, so that the front of the building embodies a great deal more material than is embodied in such buildings at a point occupied by the light well.

It is a primary object of this invention to

produce a process for moving large building structures away from the street front, wherein an intermediate portion of the building is removed and the entire front section is moved bodily over the space which was occupied by the removed portion of the building.

It is a noteworthy feature of this invention that the portion of the building which is removed may be and is preferably in a position which presents the smallest cross sectional area of the building structure.

It has been previously pointed out that the buildings in connection with which this process is particularly adapted for use consists of structures in which the building load is carried by a plurality of columns resting upon the earth and positioned in a manner such that the entire weight of the building, with the exception perhaps of the first two stories which are carried by the side walls, is supported by these columns. It will be apparent that if a building of this character were simply placed upon movable supports and moved bodily to a new position where the removable supports were replaced with permanent supports resting upon the earth, that the earth would naturally tend to settle a certain amount; and where such a building structure was attached to a similar structure which had been settling with the earth for several years, the settlement of the newly moved portion would result in a distortion of the building. Sections so moved cannot be left in an elevated position to anticipate any settlement, because floor elevations must be properly joined at time of moving.

It is therefore important in carrying out a process of this character to provide a new foundation for the building which will obviate the possibility of the settling effect mentioned above. This is accomplished in my invention by placing a permanent reinforced mat or floor below the building which covers the entire area over which the building is to be moved.

It is a noteworthy feature of the invention that the reinforcements in the floor extend transversely relative to the direction in which the building is to be moved and are so arranged as to provide supporting beams resting upon the settled soil which originally supported the columns of the moved building structure. This construction precludes the possibility of the settling of the moved building structure, even though some of the col-

umns may be finally positioned above a fault or above socalled green or unsettled soil.

- A general method which may be employed in carrying out my invention consists of re-
5 moving an intermediate section of the building and excavating the earth below and around the columns supporting that part of the building which is to be moved, at the same time placing fixed temporary supports
10 beneath the bases of such columns. The fixed temporary supports used consist of suitable jacks which are placed beneath the column in a step by step manner during the excavation of the earth.
15 During the process of excavating and placing the jacks beneath the columns, a reinforced concrete floor of suitable thickness and strength is laid upon the excavated area, and is gradually worked into the area
20 immediately below the column bases.

During this operation, as the floor sets, the weight of the columns is transmitted through jacks onto the floor itself until the earth beneath the columns has been completely re-
25 moved. At this stage of the process the entire weight of the building is supported by a plurality of jacks which rest upon the reinforced concrete floor or mat.

The jacks are then replaced with what
30 may be termed temporary movable supports in the form of beams which extend parallel with the direction in which the building structure is to be moved, such beams being supported by suitable metal rollers. At the
35 end of this operation, the weight of the building structure is carried by a plurality of movable supports which in turn are supported by the concrete floor.

The building structure is then moved in
40 any preferred manner, such as by means of a plurality of angularly positioned jacks into the desired position, after which the temporary movable supports are replaced with what may be termed permanent supports
45 which are preferably in the form of a plurality of interlocking beams positioned beneath the column bases. After underpinning the building onto the so-called permanent supports, a filling material such as concrete
50 is placed in and about the supports to guard against the possibility of slippage of the building structure upon its new foundation.

It is a noteworthy feature of the invention that the movable supports which carry
55 the columns during the movement of the building are of a form such that they may be extended below the walls of the building, forming a cantilever beam which supports the walls during the moving operation.

60 The manner of practicing a preferred method contemplated by my invention, will be best understood from the following description of the accompanying drawings which are chosen for illustrative purposes
65 only and exemplify various steps which I

have found to be most satisfactory in the practice of my invention.

Fig. 1 is a diagrammatic plan view of a building, a portion of which is to be moved.

Figs. 2 to 9, inclusive, are diagrammatic 70 plan views illustrating the various steps employed in placing the building upon temporary movable supports which rest upon a permanent reinforced mat or floor.

Figs. 10 to 17, inclusive, are sectional ele- 75 vational views showing the various steps illustrated in Figs. 2 to 9, inclusive.

Fig. 18 is an elevational view illustrating a building structure which is supported prior to movement. 80

Fig. 19 is a sectional elevation illustrating the manner in which the building is supported after it has been moved to its final position.

Fig. 20 is a sectional elevation which may 85 be considered as having been taken substantially in a plane represented by the line 20—20 in Fig. 19.

More particularly describing the invention as herein illustrated, reference numeral 20 90 indicates a building, a front section 21 of which is to be moved.

The building 20 may be generally described as embodying a front wall 22, a rear wall 23, and side walls 24 and 24' respectively. 95

The building is illustrated as being provided with a plurality of columns generally indicated by reference numeral 25 which carry the entire weight of the building with the exception, perhaps, of the first two stories, 100 which are supported by the walls 22, 23, 24 and 24'.

The building 20 is illustrated as being provided with a light well 26, and in buildings of this character where the front section 21 is 105 to be moved away from the street, it is preferable to remove a portion of that section of the building which is occupied by the light well.

The removed section is generally indicated in Fig. 1 by reference numeral 27, and the front section 21 is illustrated as being supported by means of temporary movable supporting means 28 which are positioned beneath the columns 25'.

The first step in carrying out my invention 115 includes the strapping and bracing of the columns to prevent the possibility of relative transverse movement between the columns during the excavation of the earth and the subsequent moving of the building. Such 120 strapping and bracing construction is illustrated as comprising horizontal braces 29 and diagonal braces 29', which are positioned between adjacent columns and tie rods 30 also positioned between adjacent columns and provided with a turnbuckle 31 for drawing the tie rods into position.

After the columns have been braced in this manner, the earth in the alleys between the column bases is excavated to a substantial 130

distance below the bottom of the columns, as indicated in Figs. 2 and 10. This excavation is carried a slight distance beneath the inner edges 35 of the column bases, the distance to which such excavation is carried being sufficient to admit the placement of retaining walls 36 below the columns and in contact with the earth which remains thereunder.

Rows of jacks indicated by reference numeral 37 are positioned against the retaining walls 36 upon purlin members 38 in the manner illustrated in Fig. 10.

It will be noted from Fig. 10 that the purlin members 38 are positioned in a manner such that their outer surfaces 39 are set a substantial distance beneath the lower face 40 of the column base, this distance being substantially the width necessary to support another row of jacks, as will be hereinafter pointed out.

Figs. 3 and 11 illustrate the manner in which a part of the concrete mat or floor is positioned in the alleys between the columns and below the inner edges of the rows of columns.

It will be noted that the mat section 41 is provided with longitudinally extending reinforcements 42, which are preferably in the form of steel beams or rails, and it is also to be understood that these reinforcements preferably extend transversely relative to the direction in which the building is to be moved. The purlin members 38, it will be observed, comprise forms for the outer edges of the mat section 41.

After the construction has been carried to the point illustrated in Figs. 3 and 11, the mat section 41 is permitted to set and harden, it being understood that a similar operation may be carried out in another part of the building while the prepared section is setting.

After the mat section 41 has set sufficiently to support a substantial weight, a row of jacks indicated by reference numeral 44 is interposed between the outer edge of the column base and the outer edge of the mat section 41.

After the column has been supported in this manner, the unit is ready for another excavation step which is preferably carried out on sides of the columns which are opposite to the mat section 41. Such excavation step is similar to that described in connection with Figs. 2 and 10, and a similar set of jacks and purlin members indicated by reference numerals 45 and 46 respectively, and form members 47, are positioned beneath what may be termed the outer edges of the column bases.

The mat sections 48 and 49 are then placed in the outer alleys, as described above, in connection with Figs. 3 and 11, and after the mat sections 48 and 49 have set and hardened, the outer rows of jacks indicated by reference numerals 50 and 51 are interposed be-

tween the outer edges of the column bases and the mat sections 48 and 49 in the manner illustrated in Figs. 5 and 13.

When the columns have been supported in this manner, an inner row of jacks such as 70 the row indicated by reference numeral 45 is removed. This admits the removal of the purlin members 46 and the form members 47 after which the excavation of the material beneath the columns is carried inwardly a 75 sufficient distance to permit the extension of the mat members 48 and 49 beneath the column a sufficient distance to support another row of jacks in a manner illustrated in Figs. 6 and 14. This step by step excavation process followed by the placement of extensions 80 on the mat members and cooperating rows of jacks is carried on until all of the columns are completely supported by jacks resting upon a reinforced mat or floor which covers 85 the entire surface over which the building is to be moved.

After the columns are supported in this manner as indicated in Figs. 7 and 15, the jacks generally indicated by reference numeral 60 are replaced in a step by step manner with what may be termed movable temporary supports each of which is in the form of a plurality of beam sections extending parallel with the direction in which the building is to be moved and generally indicated by reference numeral 28.

The construction of this movable support is perhaps best illustrated in Fig. 18 as comprising a plurality of interconnecting I-beams 61 connected by means of plates 62 and resting upon horizontal plates 63.

A plurality of roller members 64 are positioned beneath the horizontal plates 63 and are adapted to rest upon longitudinally extending rails 65.

It will be noted that the rails 65 and the beams 61 extend substantially at right angles to the permanent reinforcements 42 in the mat or floor. Fig. 18 also illustrates the manner in which the movable supporting beams 61 extend outwardly beneath a front wall 22 forming a cantilever support for this wall.

The manner in which the temporary movable supporting members are positioned beneath the columns is perhaps best illustrated in Figs. 8 and 16 and 9 and 17 respectively. I consider it preferable in positioning these members to first remove a sufficient number of jacks from the center portion of the column base and to substitute therefor a set of rails 65 and supporting rollers 64 which in turn carry plates 63 upon which the beams 61 are mounted.

This process of substituting the removable members for the jacks or temporary fixed supports is carried out until the columns are completely supported by the temporary movable supports in the manner indicated in 130

Figs. 9 and 17. It will be understood, of course, that the number of these supporting members is dependent entirely upon the column base area and the concentrated load which the columns carry, but spaces must be left between the movable supports which will permit a subsequent insertion of jacks for substituting a permanent supporting structure for the temporary movable supports, as will be hereinafter pointed out.

After the movable members have been placed beneath the columns, I consider it preferable to drive a series of wedges between the bottom surfaces of the column bases and the upper surfaces of the beam members. Thus the beam members are held in firm engagement between the column base and the plates carried by the rollers.

After the building has been supported in this manner, the construction assumes the appearance illustrated in Fig. 18, and is ready to be moved.

Movement may be imparted to the building structure in any suitable manner, such as by positioning a series of jacks 70 between the outer ends 72 of the beams 61 and suitable base members 73 positioned outside of the building. This construction may be used to move the building the required distance which, in the case illustrated, would be to a point at which the two broken edges 73 and 73' of the side walls 24 and 24' are brought substantially into engagement with each other.

After the building has been moved to this point, the temporary movable supports 28 are replaced with a permanent supporting structure illustrated in Figs. 19 and 20 as comprising a series of interlocking I-beams 75. The operation of replacing the temporary support with the I-beams 75 is similar to that described for the original positioning of the temporary supports. The temporary supports may first be replaced with jacks, which are then replaced in a step by step manner with the I-beams 75 which, in turn, are locked with each other by means of tie bolts 76, the I-beams 75 being held in spaced relation by means of spacers indicated by reference numerals 77.

After all of the columns have been positioned upon the I-beams 75, the space about the I-beams and the intermediate spaces between the I-beams is filled with concrete for the purpose of preventing the possibility of any transverse movement of the I-beams while the building is resting thereon.

It will be understood, of course, that the depth or thickness of the mat or floor 41 is governed by the concentrated load which it carries, and, as has been previously pointed out, the floor is longitudinally reinforced in a manner such that it is impossible for the building to settle after it has been placed in final position. The position of the upper sur-

face of the floor and the width of the I-beams 75 is such that the upper surface of the I-beams 75 is in the same plane with the original position of the lower surface of the column bases, so that after the building has been moved to its final position, the floors therein are on the same horizontal plane with the floors on the unmoved portion which is supported by the columns indicated by reference numeral 25 in Fig. 19.

After the concrete filling 78 has set and hardened, the space about the column bases may be filled with earth up to the original level as indicated by reference numeral 79 in Fig. 19.

From the foregoing description, it will be apparent that this invention embodies a process for shortening or moving large building structures which may be carried out without danger to the workmen affecting the moving operation.

The permanent longitudinal reinforced mat which covers the entire area over which the building is moved provides a support which obviates the possibility of the building cracking during movement or settling after it has been placed in a permanent position.

It is preferable that the reinforcements in the mat extend substantially at right angles with the permanent supporting beams which are interposed between the column bases and the upper surface of the mat, so that there is an interlacing reinforced support for the entire building which prevents the possibility of any transverse movement in the column bases due to any inequalities in the distribution of the load to the mat or floor structure.

It will be understood that, while I have herein described and illustrated one preferred means for effecting my process and described a preferred manner for moving a building structure by this process, it is not limited to the precise sequence of operations set forth above, but includes within its scope whatever changes or substitutions that may fairly come within the spirit of the appended claims.

I claim as my invention:

1. A method for moving a column supported building structure which includes: excavating beneath the columns; placing a permanent horizontally extending mat structure beneath said columns; interposing temporary movable supports between said columns and said mat; moving the building structure on said temporary supports to a predetermined position above said mat structure; and substituting permanent supports for said temporary supports.

2. A method for moving a column supported building structure which includes: excavating beneath the columns; placing a permanent horizontally extending mat structure

- beneath said columns; interposing temporary movable supports between said columns and said mat; moving the building structure on said temporary supports to a predetermined 5 position above said mat structure; substituting permanent supports for said temporary supports; and placing a filling material above said mat and about said permanent supports.
- 10 3. A method for moving a building structure which includes: placing a permanent floor below the building structure which covers the entire area over which the building structure is to be moved; interposing movable supports between the load carrying members of the building structure and said permanent floor; moving said building structure on said temporary supports to a predetermined point; and substituting permanent 15 supports for said temporary supports.
4. A method for moving a building structure which includes: placing a horizontal reinforced concrete floor below the building structure which covers the entire area over 20 which the building structure is to be moved, the reinforcements in said floor extending transversely of the direction in which the building is to be moved; interposing temporary movable supports between the load carrying members of said building structure 25 and said floor; moving said building structure on said temporary supports to a predetermined point; and substituting permanent supports for said temporary supports.
- 30 5. A method for moving a building structure which includes: placing a horizontal reinforced concrete floor below the building structure which covers the entire area over 35 which the building structure is to be moved, the reinforcements in said floor extending transversely of the direction in which the building is to be moved; interposing temporary movable supports between the load carrying members of said building structure 40 and said floor, said movable supports extending parallel with the direction in which the building is to be moved; moving said building structure on said temporary supports to a predetermined point; and substituting permanent supports for said temporary supports.
- 45 6. A method for moving a building structure which includes: placing a horizontal reinforced concrete floor below the building structure which covers the entire area over 50 which the building structure is to be moved, the reinforcements in said floor extending transversely of the direction in which the building is to be moved; interposing temporary movable supports between the load carrying members of said building structure and said floor, moving said building structure on said temporary supports to a predetermined point; and substituting permanent supports for said temporary supports.
- 55 structure which covers the entire area over which the building structure is to be moved, the reinforcements in said floor extending transversely of the direction in which the building is to be moved; interposing temporary movable supports between the load carrying members of said building structure and said floor, moving said building structure on said temporary supports to a predetermined point; substituting permanent supports for said temporary supports, and filling in about said permanent supports with concrete.
- 60 7. A method for moving building structures in which the building structure as a unit is moved bodily on a substantially solid mat covering the entire area over which the building is moved.
- 70 8. A method for moving building structures in which the building structure is finally supported in a moved position upon a substantially solid mat covering the entire area over which the building was moved.
- 75 9. A method for shortening buildings which includes: removing an intermediate section of the building, placing a substantially solid mat beneath one of the remaining sections of the building; placing temporary movable supports between the load carrying members of one of said last mentioned sections and said mat; moving the movably supported section of the building to a predetermined position; and replacing the temporary movable supports with permanent supports.
- 80 10. For use in moving column supported building structure: a continuous mat below all of the columns in said building structure; rolling means above said mat and column supporting members interposed between the lower surfaces of said columns and said rolling means.
- 85 11. For use in moving a column supported building structure: a continuous mat below all of the columns in said building structure; rails on said mat extending parallel with the direction in which the building is to be moved; rollers on said rails; and column supporting members interposed between the column bases and said rollers.
- 90 In testimony whereof, I have hereunto set my hand at Los Angeles, California, this 20th day of March, 1929.
- 95 105

GEORGE R. KRESS.
